UNITED STATES PATENT OFFICE.

ROBERT L. WHITEHEAD, OF PERTH AMBOY, NEW JERSEY, ASSIGNOR TO AMERICAN SMELTING & REFINING COMPANY, OF MAURER, NEW JERSEY, A CORPORATION OF NEW JERSEY.

ELECTROLYTIC APPARATUS.

1,206,965.

Specification of Letters Patent.

Patented Dec. 5, 1916.

Original application filed February 10, 1913, Serial No. 747,253. Divided and this application filed April 17, 1916. Serial No. 91,585.

To all whom it may concern:

Be it known that I, ROBERT L. WHITEHEAD, a citizen of the United States, residing at Perth Amboy, county of Middlesex, 5 and State of New Jersey, have invented certain new and useful Improvements in Electrolytic Apparatus; and I do hereby declare the following to be a full, clear, and exact description of the invention, such as will 10 enable others skilled in the art to which it appertains to make and use the same.

My invention relates to certain new and useful improvements in electrolytic apparatus, and particularly to the arrangement of 15 the electrodes in such apparatus and the connections for maintaining electric contact of an efficient character and of low resistivity throughout the system.

Prior to my invention, it has been customary in electrolytic apparatus for the deposition of metal from solutions (as, for instance, in the electro-metallurgy of copper, nickel, and the like) to arrange the electrolytic vats containing the solution to be 20 electrolyzed, alongside of each other, and in such relationship that the working current entered a bus-bar, with which the anodes of the first vat of the series connected. From these several anodes, the 25 working current then passed through the solution to the several cathodes of said vat, thereby electrolyzing the solution therein. The cathodes of the first vat, in these prior arrangements, rested upon and made electrical 30 connection with a supporting bar, which, in its turn, supported and made electrical connection with the anodes of the next succeeding vat in the series. The main defect in this general arrangement has been 35 that it involved a double series of electrical contacts along the common bar supporting the cathodes of the first vat and the anodes of the second vat, and so on, through the series. This difficulty is of particular importance 40 in electrolytic apparatus, for the reason that the working current employed is of relatively low voltage, so that the total loss of energy due to the large number of individual contacts called for in an extensive installation is very considerable in 45 amount and importance.

My present invention is intended to minimize this loss of energy by connecting the cathodes of the first vat of the series di-

rectly with the anodes of the second vat, and 55 so on throughout the entire installation, whereby not only is the common connecting bar of the former arrangement entirely dispensed with, but the number of contacts throughout the system is reduced to one- 60 half.

In the accompanying drawing, Figure 1 represents a partial plan view of electrolytic apparatus embodying the preferred form of 65 my improvements; Fig. 2 represents a transverse section thereof, partly in elevation; Fig. 3 represents, on a larger scale and in side elevation, the electric connection between the cathode of one of the vats and the anode of its neighbor in the series; Fig. 4 70 represents a top plan view thereof; and Fig. 5 represents a sectional view on the line 5—5 of Fig. 3.

Similar letters of reference indicate similar parts throughout the several views. 75

Referring to the drawing, A indicates the individual members of a series of electrolytic vats, forming part of an installation for electrolytic purposes, as, for instance, the deposition of metal from its solutions, 80 by means of an electric current of low voltage. The anodes a are provided with supporting lugs b, c, for suspending them in the solution. The lugs b of the anodes rest upon the bus-bar B, which supplies 85 the working current to the apparatus, and the lugs c rest upon an insulating strip d, as shown. The cathodes e are likewise provided with lugs f, connecting them to the bar g, which is thus electrically connected 90 with and constitutes a part of the cathode structure, and the ends of the bar g constitute the supports from which the cathode is suspended in the solution. One end of the cathodes rests upon the insulating strip 95 h, and the opposite end rests upon the supporting lug b of the corresponding anode in the next vat of the series. It will be apparent, therefore, that, instead of the double set of contacts incident to the use 100 of the common connecting bar of the former arrangement herein before referred to, an electrolytic apparatus provided with my improvements has but a single set of connecting contacts between the cathodes of 105 the several vats and the anodes of the corresponding neighboring vats in the series, that is to say, the single contact established

between each cathode of one vat and the corresponding anode of the next vat, so that there is a corresponding saving in energy of one-half of the loss incident to 5 the usual practice.

It will be particularly noted that my preferred connection between the cathode and anode is a wedging contact. The preferred form of this connection is fully indicated in 10 Figs. 3, 4 and 5, and, as shown therein consists of a ridge or projection *i*, cast integral with the lug *b*, coöperating with a recess *j* made on the underside of a boss *K* of the cathode bar *g*. This recess *j* is so related to the ridge or projection *i* that the 15 side walls of the recess shall come in wedging contact with the sides of the ridge or projection, and, to this end, a corresponding clearance is provided, as indicated in 20 Figs. 3 and 5. The relative conformation of the ridge or projection and of the recess permits of this wedging contact. In the instance illustrated, the result is attained by 25 making the angle of the recess smaller than the angle of the entering ridge or projection, but it will be understood that this is merely one of many other like or equivalent expedients for producing the same result, that is to say, of causing a binding or wedging 30 contact on opposite sides of the ridge or projection and between said sides and the lower edges of the recess.

I do not claim herein the form of the contact above described including the provision 35 of a wedging effect by the employment of a ridge or projection on one of the co-acting parts and a recess or groove on the other, as that form of contact constitutes the subject matter of another application filed 40 by me on February 10, 1913, and serially numbered 747,253, of which this application is a division.

I claim:

1. Electrolytic apparatus, comprising the 45 combination of a plurality of electrolytic vats provided with electrodes consisting of anodes and cathodes, the electrodes of one of the two sets having lateral projections thereon overlying portions of the electrodes 50 of the other set in the adjacent vat and bearing directly thereon by gravity to support the electrodes of the first named set and effect electrical connection between the two sets of electrodes, whereby the electrodes of the first named set may be raised vertically 55 out of their vat and are electrically disconnected from the other electrodes by so raising them; substantially as described.

2. Electrolytic apparatus, comprising the 60 combination of a plurality of electrolytic vats, a plurality of anodes in each vat having lateral projections by which they are sustained upon the walls of the vat, and a plurality of cathodes in each vat, each provided 65 with a lateral projection extending beyond

the wall of the vat and making contact directly with an anode in an adjacent vat by bearing thereon by gravity; substantially as described.

3. Electrolytic apparatus, comprising the 70 combination of two electrolytic vats, a plurality of anodes in each vat having laterally projecting lugs bearing upon the walls of the vat to sustain the anodes in the vat, and a plurality of cathodes in each vat, the 75 cathodes in one vat having lateral projections which extend over and rest by gravity upon the lugs of the anodes in the other vat; substantially as described.

4. Electrolytic apparatus, comprising the 80 combination of a plurality of electrolytic vats, a plurality of anodes in the vats each having a contact member formed integral therewith, and a plurality of cathodes in the vats each provided with a lateral extension 85 which overlies the anode of the next adjacent vat and directly engages the contact on that anode; substantially as described.

5. Electrolytic apparatus, comprising the 90 combination of a plurality of electrolytic vats having anodes and cathodes therein, and a plurality of cathode bars extending across the vats, and each having a cathode suspended therefrom, each of the cathode bars being extended so that its end will 95 rest upon and make contact directly with an anode in a vat adjacent to the vat in which the cathode suspended from the bar lies; substantially as described.

6. Electrolytic apparatus, consisting of a 100 plurality of electrolytic vats, each provided with a series of anodes having end supports and a series of cathodes, the cathodes being provided with supports which rest by gravity upon the end supports of the anodes 105 of the neighboring vat in the series and are electrically connected to the anodes solely by said gravity contact, whereby any cathode may be freely raised vertically out of 110 its vat and is electrically disconnected from the anode by so raising it; substantially as described.

7. Electrolytic apparatus, consisting of a plurality of electrolytic vats provided with anodes and cathodes, the cathodes of each 115 vat being provided with projecting portions which rest by gravity upon the anodes of the neighboring vat in the series; substantially as described.

8. Electrolytic apparatus, consisting of a 120 plurality of electrolytic vats provided with anodes and cathodes, the anodes of each vat being provided with lateral projections by which the anodes are supported in position, and the cathodes of each vat being provided 125 with projecting portions which bear by gravity upon the said projections of the anodes of the neighboring vat in the series and are electrically connected to the anodes solely by said gravity contact, whereby any 130

cathode may be freely raised vertically out of its vat and is electrically disconnected from the anode by so raising it; substantially as directed.

5 9. Electrolytic apparatus, consisting of a plurality of electrolytic vats provided with anodes and cathodes, each cathode being suspended from a bar and each such bar making a single electric contact with an anode in a vat adjacent to the vat in which the cathode suspended from that bar lies; substantially as described.

10 10. Electrolytic apparatus, consisting of a plurality of electrolytic vats provided with

anodes and cathodes, each anode being provided with lateral projections by which the anode is supported, and a plurality of bars extending across the vats and each having a cathode suspended therefrom, each of said bars projecting over an anode in a vat adjacent to the vat in which the cathode suspended from that bar lies and making a single electric contact with one of the projections of that anode; substantially as described.
